(57) **CLAIM**

The ornamental design for a polisher device, as shown and described.

DESCRIPTION

FIG. 1 is a top perspective view of a polisher device showing our new design with the handle removed for clarity of disclosure;

FIG. 2 is a bottom perspective view thereof;

FIG. 3 is a top plan view thereof;

FIG. 4 is a side elevational view thereof, as seen from the left side of FIG. 3;

FIG. 5 is a side elevational view thereof, as seen from the bottom side of FIG. 3;

FIG. 6 is a side elevational view thereof, as seen from the top side of FIG. 3;

FIG. 7 is a top perspective view of a second embodiment of a polisher device showing our new design;

FIG. 8 is a bottom perspective view thereof;

FIG. 9 is a top plan view thereof; and,

FIG. 10 is a side elevational view thereof.
